Peter Lee Bocsey
his Attorney.

UNITED STATES PATENT OFFICE

2,260,478

TABLE

Kurt Peter, Bronx, N. Y.

Application April 2, 1940, Serial No. 327,392

2 Claims. (Cl. 311—90)

This invention relates to new and useful improvements in tables, and more especially to tables of the kind, which are carried around, or set up for temporary uses for the purpose of games, such as bridge, afternoon tea, and at improvised parties, where extra table space is required.

Another object of my invention is thus to provide, what for the sake of denomination may be called a bridge table, that will not, as is now commonly the case, become shaky in course of use, but which has adjusting means that will at all times prevent such shakiness, and take up any wobbling which through extensive use and in course of time will occur with respect to the legs and the table they support.

The characteristic of said adjusting means is to the effect that said means will in a progressive way take up any slackness that may develop at the junction, where the legs are joined to the table.

A further object of the invention is to provide a table which, when not in use, may be compactly folded, and wherein a center support of said table in folding and opening the latter will automatically assume the position necessary to said table in a folded or open condition.

While the table is shown herein, as consisting of two hinged units, this table may, of course, consist of but one unit, like an ordinary bridge table.

As my invention is comparatively simple of construction, the cost of manufacturing the same should be proportionately low.

With the above and other objects in view, this invention consists of the novel features of construction, combination and arrangement of parts, hereinafter fully described, claimed and illustrated in the accompanying drawing forming part of this application, and in which similar characters of reference indicate corresponding parts in all views, and in which:

Figure 1 is an isometric view of my invention.
Figure 2 is an isometric view of the same.

Figure 3 is a transverse sectional view, taken on the line 3—3 in Figure 1.

Figure 4 illustrates the table shown in Figure 3, in folded position, part of said table having been broken off; while

Figure 5 is an elevational detail view of part of my invention.

Referring more particularly to the drawing, 10 and 10' indicate two table sections hinged together, as shown at 11 in Figure 3. A number of legs 12 are pivotally connected to said table

sections, as shown at 13, and foldable upon the latter, as may be seen in Figure 4.

The legs are at one end made with a shoulder 14, whereby to form a solid joint with the end portion 15 of the table, when said legs are in an extended position, as shown, for instance, in Figure 3. The inner surface of each side frame 16 of the table, is provided with a recess somewhat V-shaped, as may especially be seen at 17 in Figure 3. Small toothed plates 18 are arranged in close proximity to said recesses 17, and secured to the side frames 16 by screws 19.

Arms 20 are pivotally connected to the legs 12, as shown at 21. Said arms are again at the front thereof joined together by means of a cross bar 22. The arms 20 terminate at the front thereof in a hook portion 23. Said hook portion is adapted to slide with the end portion 24 thereof in the recess 17, while the front portion of said hook portion terminates in an edge 25 adapted to register with and engage the teeth of the toothed plate 18 in adjusting the table.

It will thus be apparent that on account of the relative position to which the arm 20 and the slanting toothed plate 18 may be adjusted, it will be possible to take up any slack or wobble, which in course of time, during wear and tear, may occur with respect to the junction of the legs 12 and table sections 10 or 10'. Thus by raising the arm 20 the legs 12 will be pushed back to normal or tight position, relative to the table section said legs support. In folding the legs 12 upon the table sections 10 and 10', the end portion 24 of the hook member 23 will slide forward in the recess 17, as may be noted in Figure 4.

Center legs 12' of the table, when two table sections are employed, are pivotally secured to the sides of one of said table sections, as shown at 26. A cross bar 27 connects the legs 12' together; said cross bar which has a square upper surface 30 projects half way under the end portion 28 of the table section 10', thereby securing the legs 12' in a steady position relative to said table section.

A spring 29 has one end secured to the table section 10 and the other end to the cross bar 27, as indicated at 31 and 32, respectively.

In folding the table sections together, the table section 10 will push the legs 12' slowly over, while in unfolding said table sections the legs 12' will automatically assume a vertical position on account of the action of the spring 29; the latter serves further to hold the center legs in an upright position.

When the table sections are folded together,

the table will have an appearance as shown in Figure 2, where the said sections are held in place by means of a fastening clasp 33, and a knob 34 adapted to engage the latter for said purpose.

It is obvious that changes may be made in the form, construction and arrangement of the parts, as shown, within the scope of the appended claims, without departing from the spirit of the invention, and I do not, therefore, wish to limit myself to the exact construction and arrangement shown and described herein.

What I claim as new, and desire to secure by Letters Patent of the United States, is:

1. In a device of the class described, a table comprising two units hingedly connected, legs supporting said units at both ends thereof, bars connecting said legs, each of said units being formed with a recess in each side thereof, and toothed plates secured to the table units in close proximity to the recesses, adjustable members pivotally secured at one end thereof to the legs, each of said members terminating at the other

end thereof in a hook portion adapted to engage said recesses in setting up or folding the table, and a sharp edge section formed at the end of the hook portion and made to engage the toothed plates in adjusting said table to a rigid position.

5 2. A device of the class described, comprising two table sections hingedly connected, each of said sections having side frames, legs pivotally secured to the latter, each of said frames being formed with a substantially V-shaped recess oppositely in the inner surfaces thereof, toothed plates slantingly arranged upon the inner surfaces of the side frames and in close proximity to said recesses, adjustable members having one 10 end thereof pivotally secured to the legs, each of said members terminating at the other end thereof in a hook portion adapted to engage said recesses in setting up or folding the table, and an edge section formed at the end of the hook portion and made to engage the toothed plates in adjusting said table to a rigid position.

KURT PETER.
